UNITED STATES PATENT OFFICE.

JOHANN G. PETERSON, OF HARTFORD, CONNECTICUT.

HANDLE OR BUTTON.

1,070,172.

Specification of Letters Patent.

Patented Aug. 12, 1913.

Application filed September 22, 1911. Serial No. 650,745.

To all whom it may concern:

Be it known that I, JOHANN G. PETERSON, a citizen of the United States, residing at Hartford, in the county of Hartford and 5 State of Connecticut, have invented certain new and useful Improvements in Handles or Buttons, of which the following is a specification.

This invention relates to handles or buttons such as are used in connection with snap and other types of electric switches. It is customary to make the body of such a handle or button of some composition and to connect with said body a yoke which sustains certain spring mechanism. Ordinarily 10 the old yoke or equivalent which is usually molded into the composition, fractures or breaks the same, while being cooled after baking. I provide a construction wherein 15 this disadvantage is eliminated. In my case I mold as is common, into the composition a yoke, the branches of said yoke being resilient or flexible, so that said branches will contract and expand with the composition, 20 the result being that when the composition is cooling as set forth, the said branches will contract with the composition and thereby 25 not break the same.

The foregoing is one of the principal 30 points of the present invention.

Another point is in the simplicity of construction and the ease with which the parts can be assembled.

In the drawings accompanying and forming 35 part of the present specification I have shown in detail one simple form of embodiment of the invention which to enable those skilled in the art to practice the same will be set forth fully in the following description, 40 while the novelty of the invention will be included in the claims succeeding said description. From this statement it will be clear that I do not restrict myself to the showing made by said drawings and description: I 45 may depart therefrom in several respects within the scope of my invention included in the claims following said description.

Referring to the drawings: Figure 1 is a 50 sectional view of a button involving my invention. Fig. 2 is a cross sectional view of the same on the line 2—2 of Fig. 1. Fig. 3 is a view in elevation of the primary yoke. Fig. 4 is a similar view of the secondary yoke. Fig. 5 is an edge view of said secondary yoke. Fig. 6 is a like view of a stem. 55

Figs. 7 and 8 are detail views of a spring and washer.

Like characters refer to like parts throughout the several figures.

In Figs. 1 and 2 of the drawings I have 60 illustrated in full a button or handle involving my invention, the same being denoted in a general way by 2 and comprising a body or main portion 3 which is usually made of some composition as is usual and which has 65 a cavity 4 in which certain parts herein-after described, are disposed. Among these inclosed parts is a yoke as 5 which is usually made from some metal, for example brass molded in said body 3. The yoke 5 as 70 shown is of approximately rectangular construction, although this is not material, and is set into the cavity 4, when the body 3 is in a plastic condition, and its side branches and head are embedded into the composition; that is to say the yoke 5 in its entirety 75 is molded into said composition so that when the said composition body has been baked the yoke will be a permanent, rigid part thereof. When the composition body cools 80 after baking it naturally contracts and to prevent the yoke from cracking such body, the side branches of the yoke are made resilient or bendable so as to give with said body as the same cools. 85

Preferably but not necessarily fitted within the primary or main yoke 5 is a secondary or auxiliary yoke 6, the branches of which are bent toward each other near their free ends to produce the inwardly or downwardly converging angular portions 7 and straight portions 8, said straight portions being in parallelism. The angular portions 7 are slotted as at 9, and said slots 9 are adapted to receive lugs or projections 10 95 which may as shown, be punched from the side branches or legs of the yoke 5 and extend inward therefrom. Said lugs or projections enter said slots 9 and engage the top walls thereof to thereby effectually and substantially sustain the said secondary yoke 6. The legs or branches of the secondary or auxiliary yoke in addition to the bent portions also have inwardly extending feet 11 constituting together a support or carrier for a washer hereinafter described. As intimated the secondary yoke 6 fits within the primary yoke and to facilitate its introduction thereinto said secondary yoke 6 may have opposite slots as 12 extending 100 105 110

depthwise thereof and formed respectively in the branches and transverse portion thereof. Were the slots not present, it would be difficult to introduce the secondary yoke into the primary yoke in view of the lack of resiliency at the junction between the branches and transverse portion of said secondary yoke. Owing to the presence of the slots, however, the secondary yoke can be readily inserted into the primary yoke during which motion the squared lugs or ears 10 will pass through the opposite slots 12. The secondary yoke is fitted into the primary yoke until the transverse portion of the latter abuts against the transverse portion of the former, and when this relation is nearly reached the branches or legs of the secondary yoke will be moved toward each other so that the lugs 10 will enter the slots 9 and thereby also hold the same against lateral motion.

The numeral 13 represents a stem which as is customary is interiorly threaded to receive the spindle (not shown) of a snap switch or equivalent part so that the body 3 of said button will bear against the casing of said switch. The stem or nut 13 is provided with a head 14 which may be of any suitable construction but which may as illustrated consist of a plate perforated to receive the upper reduced portion of said stem, said reduced portion being riveted or headed over the plate or head so as to securely hold said plate or head in place. The said head or plate 14 is equipped with inwardly extending lugs 15, the side edges of which bear against the lateral walls of the cavity 4 to present an effective bearing for said head and therefore for the stem 13. The transverse portions of the two yokes 5 and 6, have perforations or holes 16 and 17 respectively to receive the upper reduced riveted or staked portion of the stem 13.

Surrounding the stem 13 is a coiled spring 18 which constantly tends to retract said stem and the outer end of which in the present case bears against the head 14, while the inner end thereof bears against the washer 19 supported upon the feet 11 to which I have already referred.

The parts may be assembled as follows, it being understood that prior to assemblage the primary yoke is permanently connected with the composition body 3 and that the head 14 is connected with the stem 13. The spring 18 is placed around the stem 13 after which the washer 19 is applied. The said stem with the spring and washer con-

nected thereto is fitted within the secondary yoke 6 in such relation that the head 14 will bear against the transverse portion of said yoke 6, while the washer 19 will be supported upon the feet 11. These parts can then be connected with the primary yoke to accomplish which the yoke 6 will be thrust into the yoke 5, the slots 12 permitting the said yoke 6 to pass the lugs 10. When the transverse portion of the yoke 6 is near the transverse portion of the yoke 5, the washer 19 will be moved toward the head 14 thereby compressing the spring 18 and hence freely permitting the side branches of the yoke 6 to be moved toward each other and consequently causing the lugs 10 to coöperate with the side branches of the secondary yoke as already set forth.

It will be clear from the foregoing description that the composition body incloses a carrier which as described takes the form of a yoke, this carrier constituting a support for suitable locking mechanism for the button. The locking mechanism is frictional in type as will be understood. I might also indicate that while a composition body is greatly preferable, there may be cases where I can employ certain of the features already described in connection with a body which is not composition.

What I claim is:

1. A button, comprising a body having a cavity, a yoke fixed in said cavity, the side branches of said yoke having inwardly extending lugs, and a second yoke disposed within the first yoke and supported by said lugs, said second yoke having slots to permit the second yoke to pass by said lugs when said second yoke is inserted in said first yoke.

2. A button comprising a body having a cavity, a yoke set in said cavity, the side branches thereof having inwardly extending lugs, and a second yoke, the side branches of which are slotted to receive said lugs to thereby hold the second yoke in place, said second yoke having elongated slots formed respectively in its side branches and transverse portion, said slots permitting the second yoke to pass by said lugs when said second yoke is inserted in said first yoke.

In testimony whereof I affix my signature in presence of two witnesses.

JOHANN G. PETERSON.
